(57) **CLAIM**

We claim the ornamental design for a phone base with handset, as shown and described.

DESCRIPTION

FIG. 1 is a perspective view of a phone base with handset, showing our new design;

FIG. 2 is a partially exploded, perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

In the drawings, the claimed design is defined by the shaded surfaces; broken lines immediately adjacent shaded surfaces represent boundaries of the claim which extend to the boundary but do not include the boundary; all other broken lines depict portions of the phone base with handset that form no part of the claim.
